GUN SIGHT

Benedict F. Dalle Molle, Hamilton Field, Calif.

Application January 29, 1940, Serial No. 316,145

5 Claims. (Cl. 33—57)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a sight for guns and more particularly to a sight for antiaircraft or similar guns.

The principal object of the invention is to provide a relatively simple and compact sight that 10 may be expeditiously employed in calculating the lateral and vertical leads at which a gun must be trained with respect to a moving aerial or similar target in order to ensure placing the cone of fire emanating from the gun on the 15 target.

A further object of the invention is to employ a rear sight of the folding leaf type having a range or time of flight scale provided thereon in combination with a range finding or determining device displaceable along the scale, in the folded position of the leaf element, to set a sighting element, such as a member bearing a peep aperture, at the range of the target to the 20 scale on the leaf element whereupon the rear sight will be properly set in range when the leaf element is erected.

A still further object of the invention is to provide a front sight that is symmetrically split and so arranged that the split portions may be 25 simultaneously laterally displaced through equal angles independently of the gun in relative opposite directions to and from their normal full sight forming position overlying the axis of the bore for measuring the angular lateral rate of a moving target.

The specific nature of the invention as well as other objects and advantages thereof will clearly appear from a description of a preferred 30 embodiment as shown in the accompanying drawings in which:

Fig. 1 is a plan view of a gun provided with the sighting system of this invention and shows the front sight in its normal full sight forming 35 position and the rear sight with its leaf in the folded position;

Fig. 2 is a plan view showing the front sight in displaced position and the rear sight leaf erected;

50 Fig. 3 is a rear elevation of the rear sight with the leaf element in erected position;

Fig. 4 is a rear elevation of the rear sight with the leaf element in folded position;

55 Fig. 5 is a sectional view to enlarged scale taken on the line 5—5 of Fig. 1;

Fig. 6 is a sectional view to enlarged scale taken on the line 6—6 of Fig. 1.

Referring now to the drawings by reference characters there is shown in Fig. 1 a gun G provided with a sighting system comprising the 5 front sight 10 and rear sight 11.

The rear sight 11 includes a base 12 suitably affixed to the gun G and a rear sight leaf 13 hinged by the joint pin 14 to the base 12, as indicated in Fig. 3, for pivotal movement from 10 its folded position as shown in Fig. 4 to its erected position shown in Fig. 3. As in conventional sight leafs, the leaf 13 may be formed to have two branches 15 and 16 which are undercut as indicated at 17 for the purpose of imparting 15 lateral movement to a drift slide 18 as it is moved up or down on the leaf, thus automatically correcting for drift of a projectile fired from the gun, as is well understood in the art. The drift slide 18 may conveniently be retained 20 in the undercuts 17 by a slide member 19 adjustably secured to the leaf 13 for sliding movement to any position therealong, and is laterally movable with respect to the slide member as the latter is moved along the leaf to permit the 25 undercuts to automatically position the drift slide to compensate for drift. One or more peep 30 apertures 20 are formed in the drift slide so that the rear sight thus far described may be used, in its erected position, as a conventional sight in training the gun on relatively slow moving or stationary targets, by simply aligning the peep aperture with the graduation on the range or time of flight scale 21 corresponding to the 35 range of the target. The scale 21 may be engraved or otherwise suitably affixed on the leaf 13 in any desirable position, but for a purpose made clear hereinafter it is preferred to engrave the scale 21 on the outer edge of the branch 15 of the leaf 13 as indicated in Fig. 3.

40 A range finding or determining device operating upon the principle that the angle subtended by an object of given dimension transverse to the line of observation at a given point, is proportional to the range of the object from that point, is combined with the rear sight above described to automatically set a sight of the devices in range or time of flight during the operation of determining the range of any target 45 from the gun.

50 The range finding device comprises a rectangular range plate 22 of substantially the same transverse and longitudinal dimensions as the sight leaf 13 secured to the latter on the side remote from drift slide 18, and is formed with 55

an elongated opening 23 of general triangular shape disposed between the branches 15 and 16 of sight leaf 13 with the base of the opening adjacent the joint pin 14. A track 24 is secured 5 to the range plate on either side of opening 23 in parallelism with the adjacent side of the opening, as by the standards or ribs 25 and serve to guide the movement of substantially identical range sights 26 as they are moved longitudinally 10 of the range plate. Each range sight 26 is formed with a base portion 27 and upright sighting edge portion 28 which is arranged in normal relation with respect to the base and depends as a shank therebelow where it is terminated in a 15 guide sleeve 29 adapted to be sleeved over a track 24. To effect conjoint movement of the sights 26 longitudinally of the range plate and consequent adjustment of the lateral spacing of the sighting edges 28 thereof, a sight bar 30 having a transverse rectangular opening 31 therein is 20 secured to the slide member 19 below the peep aperture 20 and the shanks of the sights 26 are disposed in the opening 31 with the bases 27 engaging the adjacent surface of the bar whereby 25 they may freely move to and from each other as they are moved longitudinally of the tracks 24 by the slide 19 and bar 30 secured to the slide. Helical tension springs 32 or similar resilient devices are secured to each of the sights 26 and 30 sight bar 30 so as to ensure that the sights will always be maintained with their depending shanks in engagement with the longitudinal edges of opening 23 and with the sighting edges 35 28 in planes parallel with the axis of the bore of the gun. While in the embodiment of the invention herein shown the sight bar 30 has been disclosed as attached to and movable by the slide member 19 it will be understood that such disclosure is merely by way of illustration and 40 not of limitation, for if desired, the sight bar 30 may be substituted for the slide 19 by obvious mechanical expedients. In the form shown the sight bar 30 is formed with a peep aperture 33 so related to the scale 21 and sighting elements 45 26 that when the latter are properly sighted on a target the peep aperture will be aligned with the graduation on scale 21 corresponding with the range or time of flight of the target from the gun.

50 The shape of opening 23 in the range plate 22 is determined by the ballistics of the gun and average front of enemy target, against which the gun is intended to be employed, as seen by the 55 gunner or other observer at the gun for the purpose of description of which 30 feet may be assumed although this is not to be regarded as limitative in nature since any value may be employed. The base of the opening is several inches 60 forwardly of the point of observation or gunner's eye and is the chord subtended by the same angle at the point of observation or gunner's eye which subtends a target at the minimum range for which the sight is designed. This chord, 65 which is coincident with the base of the opening 23, is so located in the range plate that when the sight leaf 13 erected with the peep aperture 33 aligned with the chord and the gun trained by 70 means of the peep aperture and front sight at a target of minimum range of the sight that the gun will be properly pointed at the target with respect to the trajectory of a projectile fired therefrom. The apex portion of opening 23 includes a chord which is subtended by the same angle at 75 the point of observation or gunner's eye which

subtends the target at the maximum range of the gun, or the limiting angle of resolution of the average eye, as the case may be, and is so located in the range plate that when the peep aperture 33 is aligned therewith with the leaf 13 in erected 5 position and the gun trained by the peep aperture and front sight at a target of maximum range that the gun will be properly pointed at the target in range or time of flight with respect to the trajectory of a projectile fired therefrom. The 10 base and apex portion chords of the opening are joined by straight sides to define the opening 23 as shown, and as is obvious from inspection, any chord joining the straight edge sides of the opening will be in proportion to the range of a target, 15 subtended by the same angle at the point of observation or gunner's eye which subtends the chord, in accordance with the simple geometric proposition that in two similar triangles homologous sides are proportional. Also any chord 20 falling intermediate the base and apex portion chords will vary in ratio with respect to these chords that is proportional to the maximum and minimum ranges; from whence, ranges intermediate the maximum and minimum ranges may 25 be simply determined by moving the sights 26 up or down the range plate until the distance between them coincides with a chord intermediate the base and apex portion chords that is subtended by the same angle at the point of observa- 30 tion or gunner's eye which subtends the target. Any particular chord intermediate the base and apex portion chords of the opening 23 may be established by moving the slide 19 and sights 26 up or down the range plate 22 until the space 35 between the edges 28 of the sights 26 is subtended by the same angle which subtends the target at the point of observation or gunner's eye. The range or time of flight corresponding to the setting of the sights 26 may be read directly from 40 the scale 21 opposite an appropriate index on the sight bar 30. As more particularly shown in Fig. 3 at 34 the lower portion of the opening 23 is extended at the same chord width for a short space to facilitate positioning the sights 26 at the minimum 45 range.

The front sight 10 comprises a pair of identical sight arms 35 arranged to overlie the axis of the bore of the gun in symmetrical relation and extend from a point adjacent the muzzle of the 50 gun rearwardly to any suitable location in the proximity of the rear sight 11 where they are secured to intermeshing gears 36 suitably journaled on the gun at 37 for rotation in relatively opposed directions. For rotating the gears 36 55 and sight arms a worm wheel 38 is secured on one of the journal pins of the journals 37 and is in meshing relation with a worm 39 rotatable by the shaft 40 and knurled knob 41 or other suitable hand grasp. A front sighting element including 60 symmetrically formed sight blades 42 secured one to the forward end of each sight arm in such manner as to form a full sight overlying the axis of the bore is provided.

In the operation of a gun, against a moving 65 target, with the sighting system of this invention the gunner places the rear sight leaf 13 in its folded position and observes the target through the range sights 26, and if the space between these sights does not subtend the same angle as 70 the target he adjusts the spacing thereof by moving the slide member 19 up or down on the leaf 13 until such spacing does coincide with a chord between the sides of opening 23 in range plate 22 that subtends the same angle as the 75

target. When the sights 26 have been properly adjusted he signifies such fact to his assistant who immediately locks the gun against traversing and simultaneously therewith notes the time of flight indicated on the time of flight scale 21 by the index on bar 30 and initiates operation of a stop watch. In sequence following the determination of the range by the gunner and the locking of the gun against traversing movement by his assistant the gunner continues to track the target through the opening between the sights 26 and the appropriate sight blade 42 on the corresponding sight arm 35 by rotating the shaft 40 through the knob 41. At the expiration of the time of flight indicated on the scale 21 and determined by the gunner's assistant with the aid of his stop watch, the gunner will cease to track the target by movement of the front sight has now been displaced to a position 20 unlock the gun for traversing movement. The front sight has now been displaced to a position similar to the one illustrated in Fig. 2 in which position the sight blades 42 indicate the lateral rate of travel during the time of flight of a projectile fired from the gun in traversing the distance to the target. The gunner immediately following expiration of the time of flight measured by his assistant raises the rear sight leaf 13 and trains the gun on the target by means of the peep aperture 33 and front sight blade 42 remote from the one he tracked the target with which will point the gun with the proper lead with respect to the target. In the case of fast moving targets the initial leads calculated as above explained will serve as a basis for corrections to be applied by the gunner in pointing the gun at the target under subsequent conditions of range and angular travel. For stationary targets the range finding device may be employed in connection with a conventional rear sight as will appear from the above description.

Having now described the invention in its present preferred form what I claim is:

1. In a sighting system a front sight comprising in combination, a pair of sight arms, means for pivotally mounting the arms at their rear ends to a gun for opposed angular movement about the pivots to and from a position overlying the axis of the bore of said gun, means for simultaneously pivoting said arms about their pivots in opposed angular directions of equal magnitude and symmetrical sight blades secured to the forward ends of said arms and adapted to

abut when the arms overlie the axis of the bore to form a full sight.

2. In a sighting system a front sight comprising in combination, a pair of sight arms adapted to overlie the axis of the bore of a gun in parallel relation, intermeshing gears secured to the rear ends of the arms, means for journaling said gears to a gun, means to rotate one of said gears whereby the arms may be angularly displaced in opposite directions relative to the axis 10 of the bore of a gun and symmetrical sight blades secured to the front ends of the arms and adapted to abut in the parallel relation of the arms to form a full sight overlying the axis of the bore. 15

3. In a sighting system a rear sight comprising in combination, a leaf, a pair of separate tracks secured to the leaf in converging relation away from the base of the leaf, a sight bar secured to the leaf for longitudinally sliding movement 20 therealong, a range sight secured to each track and means for conjointly moving the sight bar and range sights longitudinally of the leaf; whereby the longitudinally positioning of the sight bar and range sights may be made to correspond with the range or time of flight of a target observed through the range sights. 25

4. In a sighting system a rear sight comprising in combination, a foldable leaf, a range plate provided with an elongated opening of general 30 triangular shape secured to the leaf with the base of said opening adjacent the base of the leaf, a track secured to the range plate in parallelism with each elongated side of the opening, a sight bar having a peep aperture and transverse opening secured to the leaf for longitudinal sliding movement thereof, a range sight provided with a shank portion secured to each track and having its shank portion engaging the elongated adjacent side of said range plate opening and 40 protruding through the opening in said sight bar, means for maintaining said shank portions in engagement with the sides of the range plate opening, and means for moving said sight bar longitudinally of the leaf. 45

5. The structure of claim 4 wherein said range sights are secured to the gun and each comprises a sighting edge disposed in a plane parallel with the vertical plane of the axis of the bore of gun and base portions joining said sighting edges engaging the sight bar outwardly of said sighting edges. 50

BENEDICT F. DALLE MOLLE.
